Electric Mfg. Co., Long Island City, N. Y., a cor-
poration of New York

Application November 12, 1948, Serial No. 149,579

Term of patent 14 years

(Cl. D48—20)

To all whom it may concern:

Be it known that I, Joseph Marino, a citizen
of the United States, residing in Brooklyn,
county of Kings, State of New York, have in-
vented a new, original, and ornamental Design
for an Attachable Reading Lamp, of which the
following is a specification, reference being had
to the accompanying drawing, forming a part
thereof, in which:

Fig. 1 is a top plan view of an attachable
reading lamp showing my new design;

Fig. 2 is a side elevational view thereof;

Fig. 3 is a front view thereof;

Fig. 4 is a rear view thereof, and

Fig. 5 is a cross-sectional view taken on line
5—5 of Fig. 2.

I claim:

The ornamental design for an attachable read-
ing lamp, as shown.

JOSEPH MARINO.
